UNITED STATES PATENT OFFICE.

WILLIAM J. BARR, OF CLEVELAND, OHIO.

DESIGN FOR A TELEPHONE-TRANSMITTER-ARM BASE.

SPECIFICATION forming part of Design No. 33,640, dated December 4, 1900.

Application filed October 20, 1900. Serial No. 33,785. Term of patent 7 years.

To all whom it may concern:

Be it known that I, WILLIAM J. BARR, a citizen of the United States, residing at Cleveland, in the county of Cuyahoga and State of Ohio, ⁵ have invented and produced a new and original Design for a Telephone-Transmitter-Arm Base; and I do hereby declare the following to be a full, clear, and exact description of the same, reference being had to the accompanying drawings, forming a part thereof.

My design pertains to the base to which the transmitter-arm of a telephone is commonly pivotally attached in use.

In the drawings, Figure 1 is a view in side ¹⁵ elevation of a base, exhibiting my novel design. Fig. 2 is an end elevation thereof, and Fig. 3 is a sectional view taken on line *x-x* of Fig. 2.

²⁰ A represents the hollow box-like body or shell of the base, which is secured to the desired support.

²⁵ B represent two lugs or ears, between which the transmitter-arm is pivoted so as to be adjustable within certain limits of height of the mouthpiece of the transmitter, and C C represent webs extending between the lugs B on each side and joining the same rigidly to

a height about equal to half that of the lugs B. All corners are rounded or relieved, as shown, and a graceful, neat, and pleasing form ³⁰ is thereby produced.

The base is usually finished by japanning or plating; but the finish, whatever it may be, forms no part of my design, which resides in the form of the base. ³⁵

The leading or material feature of my design consists in the webs C C joining the basal part of the lugs B B and merging into the top part *a* of the body of the base, as shown, thereby giving a neater finish and more attractive design ⁴⁰ than if the lugs were separated for their whole height.

Having thus described my invention, what I claim as new, and desire to secure by Letters Patent, is— ⁴⁵

The design for a telephone-transmitter-arm base as herein described and shown.

In testimony whereof I hereto affix my signature in presence of two witnesses.

WILLIAM J. BARR.
